UNITED STATES PATENT OFFICE.

WILLIAM STANDING, OF ST. LOUIS, MISSOURI.

TRACE HOLDER AND DETACHER.

SPECIFICATION forming part of Letters Patent No. 276,919, dated May 1, 1883.
Application filed August 21, 1882. (No model.)

To all whom it may concern:

Be it known that I, WILLIAM STANDING, M. D., of St. Louis, in the county of St. Louis and State of Missouri, have invented a new and Improved Trace Holder and Detacher, of which the following is a full, clear, and exact description.

The object of my invention is to provide a new and improved device for fastening and 10 detaching a trace to and from a single-tree at any desired part of the trace.

Reference is to be had to the accompanying drawings, forming part of this specification, in which similar letters of reference indicate corresponding parts in all the figures.

Figure 1 is a longitudinal side elevation of my improved trace-holder. Fig. 2 is a plan view of the same. Fig. 3 is a longitudinal elevation of a modification of the same.

Two arms, A, are hinged to the end of the single-tree B, at the top and bottom, and in the outer ends of the said arms A a roller, C, is journaled. A clamp-plate, D, which can be straight, but is preferably made curved or with 25 a convex outer surface, is provided with two studs, E, projecting from the inner surface into two barrels, F, attached to the sides of a thimble, B', secured on the end of the single-tree B. A screw, G, provided with a fixed 30 nut or head, H, at its outer end, projects from the outer end of the thimble B', and against the nut of the said screw the middle of the clamp-plate D rests. By means of the head or nut H the screw G can be adjusted to project a greater or less distance from the end of 35 the thimble B', and thereby the clamp-plate D can be adjusted a greater or less distance from the roller C, according to the thickness of the trace to be held. The arms A are bulged 40 outward between the roller C and the clamp-plate D—that is, at the part at which the trace passes through between them—so that the device can be used to hold traces which have a greater width than that of roller C and clamp-plate D. The trace which is held between 45 the clamp-plate D and the roller C is drawn in the direction of the arrow a', and is clamped tightly between the roller C and the said clamp-plate D, and will thus be held to the 50 end of the single-tree. By pulling the outer ends of the swinging arms A in the inverse

direction of the arrow a' the trace will be released, and can be drawn out from between the roller C and the clamp-plate D. Thus, if the horses become unmanageable, and they 55 are to be detached, it is only necessary to pull the roller C in the inverse direction of the arrow a' by means of a chain or cord attached to the same and leading to the driver's seat.

The above-described device is shown in Figs. 60 1 and 2. Fig. 3 shows a modification of the same.

A screw, L, is pivoted to swing between the shanks K' of the frame J, and is provided at its outer end with a nut, M. A clamp-plate, 65 N, which may be straight, but is preferably curved, is provided with two arms, N', to which an eye, O, is attached, through which the screw L passes loosely, the nut M being between the clamp-plate N and the said eye O. 70 By turning the nut M the clamp-plate N can be adjusted a greater or less distance from the roller K, according to the thickness of the trace. If the trace is to be released, the clamp-plate N must be withdrawn or swung back. 75 As the frame of the plate N is mounted on the swinging screw L, the said plate N can swing between the shanks K'. The trace can be held at any point of its length by my improved trace-holder, as no perforations or apertures 80 are required in the trace, such as are necessary for trace-holders of the usual construction.

Having thus fully described my invention, I claim as new and desire to secure by Letters Patent—

1. In a trace holder and detacher, the combination, with the single-tree B, of the bars A, pivoted to the end of the same, and connected at their outer ends by a roller, C, and of the adjustable clamp-plate D, substantially as 90 herein shown and described, and for the purpose set forth.

2. In a trace holder and detacher, the combination, with the single-tree B, of the swinging bars A, connected at the outer ends by a 95 roller, C, the clamp-plate D, and the adjusting-screw G, substantially as herein shown and described, and for the purpose set forth.

3. In a trace holder and detacher, the combination, with the single-tree B, of the pivoted 100 bars A, connected at the outer ends by a roller, C, the clamp-plate D, provided with studs E,

passing into barrels F on the end of the single-tree, and of the adjusting-screw G, substantially as herein shown and described, and for the purpose set forth.

5. 4. In a trace holder and detacher, the combination, with the single-tree B, of the hinged bars A, the connecting-roller C, and the adjustable clamp-plate D, the said bars A being bulged

outward between the roller C and the clamp-plate D, substantially as herein shown and described, and for the purpose set forth.

WILLIAM STANDING.
